UNITED STATES PATENT OFFICE

2,645,820

BLENDING HOPPER

Kenneth G. Lytton, Charlotte, N. C.

Application August 25, 1950, Serial No. 181,447

5 Claims. (Cl. 19—67)

1

This invention relates to improvements in blending hoppers.

The primary object of this invention is to provide an improved means in a blending hopper for selectively regulating the amount of flow of fiber material from the feeder apron or conveyor to the bank of rotating drums upon which tines are disposed.

Another object of this invention is to provide a series of baffles which are made in pairs of baffle sections, said plurality of baffles being so disposed with respect to each other that passages are formed between them, whereby the tines of one of a bank of rotating drums may pass through the passages, the amount of projection of the tines through the plurality of baffles being regulated by adjustment of the plurality of baffles whereby selected rates of flow of fiber material may be attained.

Ancillary objects and features of importance will become apparent in following the description of the illustrated form of the invention.

In the drawings:

Figure 1 is a perspective view of the device;

Figure 2 is a longitudinal sectional view of the structure of Figure 1 and taken substantially on the line 2—2 of Figure 3;

Figure 3 is a sectional view taken on the line 3—3 of Figure 2;

Figure 4 is a transverse sectional view taken on the line 4—4 of Figure 2 and in the direction of the arrows; and

Figure 5 is an enlarged fragmentary elevational view showing the means of adjusting the apron or conveyor and showing in phantom two positions of adjustment of the baffle assembly.

Blending hoppers are used by manufacturers employing baled fibers, such as rayon or cotton. The specific use of this particular machine is to break up the fiber into a workable condition and deliver it in a specified quantity, which is adjustable to suit the requirements of the moment. During the process, the material is partially cleaned and deposited on a conveyor or a cleaning machine.

As fiber is fed into the feed opening or inlet 10 which is defined by the case generally indicated at 12, it falls upon a moving apron or endless conveyor, generally indicated at 14. This endless conveyor is disposed in a housing 16 which consists of a top 18, a bottom 20, side walls 22 and 24 and ends 26 and 28. The inlet case 12 is formed at the lower end of the end or end wall 28, while an outlet 30 for the fiber is made by hood 32 extending around an aperture 34 in the end or end wall 26 of the housing 16.

2

The housing may be reinforced by angle iron members or other conventional structure and is provided with a vertical partition 36 having an opening 38 therein separating the partition into two sections 40 and 42. The vertical partition divides the housing 16 into compartments 44 and 46, the compartment 46 being adapted to receive the fiber, while the compartment 44 is the work compartment.

An access door 48 is provided in one of the walls of the housing near the bottom thereof, so that the bottom part of the compartment 44 may be cleaned.

A series of transverse concaves 50 are formed in the compartment 44 by means of a foraminous panel such as screen or wire mesh. The lower end of the screen or mesh is disposed on the top of the partition section 42, while the other end is hooked as at 52 over the upper edge of the end 26 of the housing.

A plurality of rotary drums 54, 55, 56, 57, and 58 are mounted on shafts transversely of the compartment 44. Each drum has a number of radially disposed tines 60 extending therefrom which work the fiber and which elevate it from the lower part of the wire mesh or screen 50 until it is discharged through the outlet 30. Any suitable means, for example, gears, chains or belts, may be employed to rotate the rotary members or drums. In Figure 3, the belting 64 is illustrated, inasmuch as belting is adequate and relatively inexpensive and silent.

There is a plate 66 attached to one side 24 of the housing and a similar plate 68 attached to the other side thereof. The plate is slotted, as is the side wall upon which the block is mounted. A standard screw 70 for each plate engages the end shaft 72 of the endless conveyor 14 in order to retain it tightened or adjusted. A similar assembly 76 is disposed on the case 12 for operation with the shaft 78 of the endless conveyor, and there is an identical assembly 79 connected with the shaft 78 and disposed on the opposite side of the case 12.

Means for regulating the amount of fiber which is taken from the conveyor 14 and pushed upwardly through the series of concaves 50 to the outlet 30 is connected between the apron 14 and the rotary member 58. This regulating means consists of a baffle assembly having plurality of baffles which are arranged in series to form first and second baffle sections. Each baffle 80 of the assembly is made from a first baffle unit 82 which is connected to a second or upper baffle unit 84 by means of a standard hinge 86. The baffle unit 82 is arranged parallel with the

next adjacent baffle unit 88 but is spaced therefrom in order to form a passage 90 therebetween.

A rod 92 is secured to the upper baffle section and is passed through a pair of slots 94, one being provided in the wall 22 and the other being provided in the wall 24 of the housing 16. Accordingly, the rod 92 is capable of sliding vertically, thereby hingedly moving the two sections of the baffle assembly. Conversely, the rod 92 is slideable vertically in response to pivotal movement of the sections of the baffle assembly.

A shaft 98 is secured to the lower edge of each baffle unit of the first baffle section and is mounted for rotation in bearings 100, said bearings being carried by a suitable structural framing element of the housing 16 on the side walls 22 and 24 thereof. An arm 102 is fixed to the shaft 98, whereby, upon movement of the arm 102, the shaft 98 will be rotated, thereby hingedly or pivotally actuating the baffle sections to the selected position.

A locking device is employed to hold the arm 102 in selected positions. The simple screw-type locking device disclosed in Figure 5 has been found to be preferable in view of its positive action and minimum of expense. A bracket 104 is fixed to one side wall of the housing and there is a screw 106 mounted for rotation therein, the outer end of the screw contacting the arm 102. A bracket 108 is secured to the same side wall of the housing 16 and has the screw 110 mounted for rotation therein. This screw, however, contacts an opposite surface of the arm 102, to thereby prevent the arm from movement in one direction. The screw 106 prevents the arm 102 from moving in the other direction.

In operation, after the fiber is placed on the apron or conveyor 14, it will move in the direction of travel of the conveyor and form a bank against the baffles. When the baffles are in the position as disclosed in Figure 2, the tines 60 of the rotary member 58 do not project through the passages 90. Accordingly, no fiber is conveyed by the set or series of rotary elements in the chamber 44. But, when the baffles are hingedly operated so that a small amount of the length of the tines 60 of the rotary drum 58 project through the passages 90, some of the fiber in the bank of fiber is pulled from the bank and pressed upwardly and inwardly of the concaves 50, thereby cleaning and working it while conveying it to the outlet 30. When the baffles are moved even farther so that more of the tines 60 of the drum 58 project through the passages 90, a larger quantity of fiber is drawn from the bank and pressed in the concaves 50 and urged upwardly until said larger quantity of fiber is discharged through the outlet 30.

Having described the invention, what is claimed as new is:

1. A blending hopper comprising a housing having a fiber stock inlet, an outlet and a conveyor vertically spaced below said inlet, and means for delivering the fiber from the conveyor to said outlet including a plurality of rotary members carried by said housing, one of said members being disposed adjacent to said con-

veyor and having a plurality of tines, a baffle assembly having a plurality of passages and disposed between said one of said rotary members and said conveyor to stop the movement of fiber in said housing and thereby form a bank of the fiber, and said tines being operable in said passages to draw some of the fiber from said bank, said baffle assembly comprising a first and a second baffle section having confronting ends hingedly connected together, and means for moving the first section hingedly relative to the second section causing said baffle assembly to move inwardly toward said one of said rotary members to increase the amount of penetration of said tines into said passages and hence into the bank of material.

2. The combination of claim 1 and said last-mentioned means including a shaft fixed to said first baffle section, and an arm secured to said shaft and located exteriorly of said housing.

3. The combination of claim 2 and means for holding said arm in selected positions.

4. The combination of claim 3 and said second baffle section having a rod secured thereto, and means mounting said rod for limited movement in said housing.

5. In a blending hopper which includes a housing having an inlet and outlet and a conveyor located between said inlet and said outlet, an agitating and delivery assembly located in said housing to deliver materials from said conveyor to said outlet, said assembly including a rotary member with tines extending therefrom, means arranged between said rotary member and the discharge end of said conveyor for regulating the rate of delivery of said tines, said regulating means including a plurality of baffles spaced from each other to thereby refine passages, said baffles being arranged with respect to said tines so that said tines are operable in said passages, said baffles comprising a first baffle section and a second baffle section, said baffle sections having confronting ends which are pivotally connected together, means for pivotally moving said first and second baffle sections with respect to each other to thereby move said baffle sections toward and away from said tines so that the amount of penetration of said tines into said passages may be increased and decreased selectively, and said baffles constituting an abutment for material on said conveyor whereby the rate of delivery of said tines may be controlled in response to the amount of relative movement between the tines and said first and second baffle sections.

KENNETH G. LYTTON.
